(57) **CLAIM**

An ornamental design for a jewelry cleaner, as shown and described.

DESCRIPTION

FIG. 1 is a front view of a jewelry cleaner.

FIG. 2 is a side view of a jewelry cleaner, the opposing side being a mirror image.

FIG. 3 is a back view of a jewelry cleaner.

FIG. 4 is a top view of a jewelry cleaner; and,

FIG. 5 is a bottom view of a jewelry cleaner.

The broken lines in FIG. 5 are for illustrative purposes only and form no part of the claimed design.
